UNITED STATES PATENT OFFICE.

RALEIGH J. HIMMELRIGHT, OF NEW YORK, N. Y., ASSIGNOR TO AMERICAN ARCH COMPANY, A CORPORATION OF DELAWARE.

ARCH BRICK.

Original application filed May 23, 1922, Serial No. 563,043. Divided and this application filed January 8, 1925. Serial No. 1,146.

This invention relates to the arch brick such as commonly used in locomotives and is a division of my application Serial No. 563,043, filed May 23, 1922, which illustrates 5 the method of manufacturing the arch bricks shown herein.

The common form of arch brick is made in one piece and owing to the large sizes of some of the bricks there are difficulties in the manufacture owing to liability of the bricks, while still plastic, to lose their shape in handling. Heretofore, it has been practically impossible to manufacture these large size bricks on machines, owing to this difficulty.

15 Another disadvantage incident to the present form of brick is that in service these bricks are subject to the very high temperature of a locomotive fire box and consequently are constantly expanding and contracting with the 20 variations of the temperature. The cumulative effect of the strains caused by this expansion and contraction results in spalling or chipping ordinarily, and in some cases, breakage of the brick.

25 It is the primary object of my invention to overcome these difficulties by the provision of a sectional or laminated brick which can be manufactured by machine and in which the strains encountered in service are, to a certain extent, reduced and the cumulative effect over the whole brick is eliminated. In other words, by building the brick in sections the strain is localized in each section and prevented from spreading over the entire brick.

30 Another object of my invention is the provision of a laminated brick in which the units are provided on contacting surfaces with cooperating projections and recesses by means of which the bricks are held in position prior to bonding.

35 A further object is the provision of a laminated brick which can be made in different shapes and sizes, adapted for use in different places in the fire box and for different tube spacings.

40 These, together with such objects as may hereinafter appear, or are incident to my invention, I attain by means of a construction, the preferred embodiments of which are illustrated in the accompanying drawings, wherein

45 Fig. 1 is a partial vertical transverse section through a locomotive fire box illustrat-

ing an arch composed of my improved bricks; Figs. 2, 3 and 4 illustrate the units and a brick 55 known as the "M" pattern; Figs. 5 and 6 illustrate the same pattern of brick but with pattern marking used to hold the units in place prior to bonding; Figs. 7, 8, 9, 10 and 11 illustrate a brick made of alternate long and short 60 units and show various uses to which this form of brick may be put; Fig. 12 illustrates another manner in which long and short units may be assembled to form a brick; Figs. 13, 14, 15 and 16 illustrate a half tongue and 65 groove laminated brick; Figs. 17 and 18 illustrate a laminated side brick and Fig. 19 illustrates what is known as a curved middle brick.

In Fig. 1 I have illustrated the usual type 70 of locomotive fire box A with the arch supporting tubes 1 upon which is supported the arch B composed of my improved bricks. These bricks are made of laminæ or units 2 (see Figs. 2, 3 and 4) by applying a suitable bonding material such as high temperature furnace cement commonly used in the art to the surfaces of the individual units 2 and then stacking these units to form the brick, a brick composed of four units being 75 a common size. One side of each unit 2 is provided with one or more projections 3 and the opposite side is provided with corresponding recesses 4, the projections on one unit fitting into the recesses on the adjacent unit to 80 hold them in place during handling prior to bonding. As illustrated in Figs. 5 and 6 and 85 14 to 18 these projections and recesses may take the form of the pattern marking of the brick.

90 Each of the sections or plates is formed with a tube engaging surface 5 and when assembled the complete brick will present a tube engaging surface along the entire end, as illustrated in Figure 4.

95 After the individual sections have been formed and stacked in proper relation to make the particular form of brick desired the brick is burned and the bonding material set in a manner well known in the art. If desired the individual sections may be burned before they are stacked and the bonding material then applied and fixed.

100 The brick so far considered, shown in Figure 4, is only one of the many forms required for locomotive arches. Another form is illus-

trated in Figs. 7, 8 and 9 which is composed of alternate long and short units 6 and 7. At one end these units are all placed flush so that the brick at this end presents a continuous 5 supporting surface. At the other end the units project alternately, the supporting surface of one unit extending beyond that of the adjacent units. A brick of the character illustrated in Fig. 8 can be used in combination 10 with similar bricks in the manner illustrated in Figure 9. Here the continuous supporting surface of the brick rests on the tube and with the bricks in leaning position the alternate projecting portions of one brick will 15 fit into and engage the recessed portions of the cooperating brick and the bricks thus held in position.

This type of brick may also be used as illustrated in Fig. 10 where one brick spans the 20 distance between two tubes, the projecting units supporting the brick at one end. If desired the projecting portions of the brick may be chipped or knocked off and the brick used to take care of a shorter span, as illustrated 25 in Fig. 11. In this case the tube engaging surfaces of the shorter units support one end of the brick.

In Fig. 12 is illustrated a brick composed of alternate long and short units but in this 30 case the longer units project beyond the shorter at both ends of the brick.

In Figs. 13 to 16 a half tongue, half groove form is illustrated. Two units are made with a projecting tongue 8 and two units with a 35 groove 9 and these four units are arranged as shown in Fig. 13 to form a complete brick which has at one end a tongue extending half way across the width of the brick and a groove extending across the other half of the width 40 of the brick. The brick may be assembled in pairs in reversed relation with their inner ends

leaning against each other, the tongue in one brick fitting into the groove in the other.

The side brick 10, illustrated in Fig. 17 is made up of units illustrated in Fig. 18. This 45 brick is used between the outside tube and the side sheet, the surface 5 resting on the tube and the surface 11 resting against the side sheet, the brick being in leaning position.

Fig. 19 illustrates a unit used to make a 50 brick similar to that shown in Fig. 4 but in this case the brick is curved instead of being flat.

I claim:

1. A refractory member composed of laminæ of different lengths. 55
2. An arch brick composed of a plurality of long units and a plurality of short units alternated. 60
3. A laminated arch brick composed of units having a tongue and other units having a groove and all arranged to form a half tongue and groove brick for use in spans where two bricks are assembled in reversed relation to lean against each other. 65
4. An arch brick constructed of laminæ of different lengths which are arranged to provide a support engaging surface at one end and projecting and receding support engaging surfaces at the other end. 70
5. An arch brick constructed of laminæ of different lengths which are arranged to provide a support engaging surface at one end and projecting and receding support engaging surfaces at the other end, the receding surfaces making the brick accommodable to a span of less dimension when the projecting surface is broken away. 75

In testimony whereof, I have hereunto signed my name.

RALEIGH J. HIMMELRIGHT.
